UNITED STATES PATENT OFFICE

LARRY VENDITTI, OF PHILADELPHIA, PENNSYLVANIA

AQUARIUM

Application filed December 19, 1931. Serial No. 582,030.

This invention relates to aquariums, and has for an object to provide an aquarium including an integral container and improved type of supporting base.

5 A further object of the invention is to provide an aquarium having an improved type of integral container, with illuminating dome therein, and a base for supporting the same.

10 A further object of the invention is to provide a base for an aquarium comprising a table structure having an illuminating element therein, with uprights having guideways, and a container fitting and sliding in the guideways and provided with a dome for covering the illuminating element.

15 The invention therefore comprises a base constructed as a table, or the like, having upstanding posts arranged thereon, with the grooves or guideways therein, and with an illuminating element extending upwardly through an opening in the table and with an integral transparent container fitting and 20 sliding in the guideways of the post, and provided in its bottom with a dome fitting over and covering the illuminating element.

25 The drawings illustrate an embodiment of the invention, and the views therein are as follows:

30 Figure 1 is a top plan view of one embodiment of the present invention,

35 Figure 2 is a view of the embodiment of the invention, shown at and as indicated by arrow 2 at Figure 1, seen in elevation,

40 Figure 3 is a sectional view, taken on line 3-3 of Figure 1,

45 Figure 4 is an inverted plan showing a fragment of the base, and the manner of inserting and securing the illuminating element therein,

50 Figure 5 is a top plan view of a base of slightly modified construction,

55 Figure 6 is a sectional view, taken on line 6-6 of Figure 5, and

60 Figure 7 is a sectional view, taken on line 7-7 of Figure 5, showing the container in position.

65 Like characters of reference indicate corresponding parts throughout the several views.

In the present invention, a supporting base is provided which includes a table structure of any approved size and shape. As shown in the drawings, at Figures 1 to 4 inclusive, this forms a triangular base 10, but the invention is not limited to such triangular form. About the margin of the table 10, an upstanding rib 11 is provided, forming a depression, conforming in general shape to the shape of the base. At the several corners, posts 12 are erected. These posts will conform in number to the shape of the base, and the showing in the drawings of three of these posts are merely in conformance with the triangular shape, and are no limitation upon the invention. The posts are provided with vertically disposed grooves or guideways 13, and the posts themselves may be of any construction found desirable. As shown in the drawings, the posts are indicated as of hollow construction, and under some conditions, this will be found an approved type and may, if constructed of transparent or translucent material, be used for containing an illuminating element.

70 Through the bottom of the table 10, an opening 14 is provided, and an illuminating element indicated at 15 as an electric bulb is inserted therethrough. This illuminating element may be supported therein and thereby raised to predetermined height above the level of the table in any approved manner. As shown, a socket 16 is provided, supported by a strap 17, and as shown at Figure 4, cut-outs 18 permit the insertion therethrough of tongues 19, carried at the extremities of the strap. By inserting through these cutouts 18 and giving a partial turn, the illuminating element will be retained in position.

75 The container is preferably an integral structure as shown at 20 and will, of course, to function properly as an aquarium, be transparent. At the present time, of course, the container would be understood as being constructed of glass. In the bottom, and upstanding therefrom, a dome 21 is erected, properly positioned to cover the illuminating element 15 when the container is in position. At Figure 2 this container is shown

as partially lifted from its normal position, indicating that the container may be removed from the base for cleaning, or the like, and by such lifting as shown, exposing 5 the illuminating element which is wholly enclosed when the container is in normal position. While forming no particular part of the invention, feet or supporting members 22 are shown as being formed in any approved 10 manner beneath the table 10. The electrical connections or circuits for the illuminating element have not been shown, but will be fully and completely understood by one skilled in the art.

15 In the modified type shown at Figures 5 to 7 inclusive, the base is of slightly different construction. As shown, a table 23 is provided, having at the corners upstanding posts 24. These posts 24 differ from the 20 posts 12 in that they are simply curved members or plates embracing the corners of the container 20. Preferably, these posts 24 will extend only a limited distance from the base as distinguished from the posts 12 25 which are shown as extending the length of the container. Under the table 23, a supporting arrangement will be provided. At the corners, parts analogizing legs 25 are shown, and intermediate the corners, other 30 parts 26. It is understood, of course, that this base, while conforming to the general shape of the container, be that what it may, will be supported by any type of supporting structure, and that the parts 25 and 26 as 35 shown, are merely illustrative. Whatever the structure, a rib 27 will be interposed between the several posts so that the container 20 will fit more or less snugly within this rib, which in conjunction with the posts, is continuous throughout the entire margin.

Of course, the aquarium, herein illustrated, may be modified and changed in various ways without departing from the invention herein set forth and hereinafter claimed.

45 The invention is hereby claimed as follows:

1. An aquarium including a support comprising a table having an opening therethrough, a lighting element, means secured 50 to the table fixing the lighting element in the opening to stand above the table, spaced container-guides adjacent to the edges of the table, and a container removably sitting upon the table and including a transparent 55 dome overlying and surrounding the lighting element.

2. An aquarium including a support comprising a table having an opening therethrough, a lighting element, means secured 60 to the table fixing the lighting element in the opening to stand above the table, spaced container-guides adjacent to the edges of the table having grooves in their proximate sides, and a container having edges complementary to and disposed in the grooves re-

movably sitting upon the table and including a transparent dome overlying and surrounding the lighting element.

3. An aquarium including a support comprising a table having an opening therethrough, 70 a lighting element, means secured to the table fixing the lighting element in the opening to stand above the table, spaced container-guides adjacent to the edges of the table having grooves in their proximate 75 sides, marginal ribs about the table having their inner edges in alignment with the sides of the grooves, and a container removably sitting upon the table within the ribs, and including a transparent dome overlying and 80 surrounding the lighting element.

4. An aquarium including a support comprising a table having an opening therethrough, 85 a lighting element, means secured to the table fixing the lighting element detachably in the opening to stand above the table, spaced container-guides adjacent to the edges of the table having grooves in their proximate sides, marginal ribs about the table having their inner edges in alignment with the sides of the grooves, and a container having edges complementary to and disposed in the grooves removably sitting upon the table within the ribs, and including a transparent dome overlying and 90 surrounding the lighting element.

In testimony whereof I have signed my name to this specification.

LARRY VENDITTI.
